UNITED STATES PATENT OFFICE.

EDWIN A. RUTENBER, OF MILWAUKEE, WISCONSIN, ASSIGNOR TO A. J. LINDEMANN & HOVERSON COMPANY, OF MILWAUKEE, WISCONSIN, A CORPORATION OF WISCONSIN.

DESIGN FOR AN ELECTRIC RADIATOR.

Application filed April 28, 1923. Serial No. 6,006. Term of patent 14 years.

To all whom it may concern:

Be it known that I, EDWIN A. RUTENBER, a citizen of the United States, residing at the city of Milwaukee, in the county of Milwaukee and State of Wisconsin, have invented a new, original, and ornamental Design for Electric Radiator, of which the following is a specification, reference being had to the accompanying drawing forming part hereof.

Figure 1 is a front view of an electric radiator illustrating my new design; Figure 2 is a side elevation thereof.

I claim:

The ornamental design for an electric radiator as shown.

Signed at the city of Milwaukee, in the county of Milwaukee, and State of Wisconsin, this 25th day of April, 1923.

EDWIN A. RUTENBER.
